CLAIM

The ornamental design for a grinder plate and cleaner
accessory assembly, as shown.

DESCRIPTION

FIG. 1 is a perspective view of a grinder plate and cleaner
accessory assembly according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

1 Claim, 5 Drawing Sheets
